UNITED STATES PATENT OFFICE.

CHARLES THOMAS MASON, OF SUMTER, SOUTH CAROLINA, ASSIGNOR TO SPLITDORF ELECTRICAL COMPANY, OF NEWARK, NEW JERSEY, A CORPORATION OF NEW JERSEY.

COMBINATION COIL AND CONDENSER FOR DYNAMOS.

1,225,457.

Specification of Letters Patent.

Patented May 8, 1917.

Application filed January 7, 1916. Serial No. 70,801.

To all whom it may concern:

Be it known that I, CHARLES THOMAS MASON, a citizen of the United States, residing at Sumter, in the county of Sumter and State of South Carolina, have invented 5 certain new and useful Improvements in Combination Coils and Condensers for Dynamos, of which the following is a specification, reference being had to the accompanying drawing.

This invention relates to a combined coil and condenser for use in an electrical dynamo and has for its objects the positioning of the condenser nearer the primary winding of the coil than has heretofore been accomplished, the support of the condenser by the coil, and the combination of the coil and condenser in such a manner that the condenser is readily removed from the coil 20 without unsoldering any connections.

For the sake of illustration I show the invention as used in connection with an ignition dynamo of the type shown in my pending application No. 14,409 of 1915, but 25 it is obvious that same may be employed in connection with any type of dynamo used for any purpose, in which a combined generating winding and condenser may be advantageously employed.

30 In ignition dynamos of the type shown in the hereinbefore mentioned application, the field structure carrying the windings is movable about the axis of the rotating polar extremities of the magnet for timing purposes. This movable field structure is provided with two upwardly projecting pole pieces across which is placed a core carrying the generating windings. It is necessary to use a condenser in the primary circuit of such a dynamo and this condenser has heretofore been mounted on some part 35 of the machine frame work, or in the cover of the breaker box or interrupter. Considerable difficulty has heretofore been encountered in suitably associating the condenser directly with the primary winding, although such an arrangement is obviously much to be desired as it not only eliminates circuit connections, but also places the condenser in a generator of the above-mentioned type up out of the way, and directly connects same across the terminals of the primary winding in a position to insure the most efficient result.

55 In the accompanying drawings, Figure 1

is a view partly in section showing a magneto embodying this invention. Fig. 2, a top view of the combination coil and condenser structure. Fig. 3 is an end view of Fig. 2. Like figures of reference denote 60 the same parts wherever they are shown.

1 and 2 denote the pole pieces of a field structure movable about the shaft 3 for timing purposes. Connecting the top of said poles is the core 4 provided with suitable 65 heads 5 and 6, preferably of insulating material. Between said heads and suitably attached thereto is the insulating plate 7 upon which is mounted contact sector 8 arranged to contact with a suitably fixed terminal 70 carried on the frame work of the machine so that sector 8 is always in engagement with said terminal as the coil is moved when timing. The arrangement of the sector and fixed terminal does not relate specifically to 75 this invention, and are not shown here, but are fully described and claimed in my pending application hereinbefore mentioned.

Mounted upon one of the heads of the coil is a suitable terminal 9 to which one end 80 of the primary winding is attached. The other end of the primary winding is attached to or "grounded" upon core 4.

The condenser 10 may be constructed in any suitable manner, and the terminals 11 85 and 12 of same are so shaped and positioned that they connect to terminal 9 and core 4, respectively, thereby electrically connecting the condenser directly across the terminals of the primary winding. It will also be observed 90 that the attaching means such as the screws 13 and 14 also mechanically secure the condenser in place, so that it is securely held in position on the coil and moves therewith.

95 It will also be observed that the screw or other means 14 makes a metallic connection from the condenser to the pole piece 1 and to the metallic body or frame work of the generator thereby electrically connecting 100 one side of the primary and condenser to the grounded side of the circuit interrupter mechanism. The insulated contact of the interrupter is connected in any suitable manner to terminal 9. As such arrangements 10 are already known, as is also the operation of a machine of this description, I do not describe same here.

From the foregoing description the advantages of my invention will be apparent 11:

to those skilled in the art, especially as regards the compact arrangement attained, the accessibility of the condenser (as it may be easily renewed), the elimination of any extra supports heretofore necessary for the condenser, and the elimination of extra contacts and connections. And while I have showed a preferred embodiment of my invention, it will be understood that all changes and modifications which do not depart from the spirit thereof, are included in the scope of the appended claims.

Having thus described my invention what I claim and desire to secure by Letters Patent is:—

1. In a dynamo, a removable core, a generating winding about said core, and a condenser associated with said core and winding, said condenser being removable with said core and winding and removable from said core and winding.

2. In a dynamo, a removable core, a generating winding about said core and supported wholly thereon, a condenser having terminals connected with said winding and core and supported thereby, said condenser being removable with said core and winding and removable therefrom.

3. In a dynamo, a generating winding, a core therefor, heads supporting said winding, terminals on said heads, and a condenser across said heads and connected to one of said terminals and to said core, substantially as described.

4. In a dynamo, generating windings, a core therefor, heads on said windings, an insulating block between said heads, a conducting segment carried upon said block, a condenser mounted on said windings and heads and supported thereby, and connections between the terminals of said coil and the segment, the condenser, and core.

5. In a dynamo, a structure adapted to be removed as a unit and comprising a core, a generating winding about said core, enclosing heads for the winding, said heads

carrying terminals and a condenser connected to said structure and supported thereby.

6. In a dynamo, movable pole pieces, a coil having a core, said core adapted to move with said pole pieces, windings on said core, a condenser carried on said windings, and means for securing said core to said pole pieces, said means also serving to electrically connect one of said condenser terminals to said core.

7. In a dynamo, a unit coil structure comprising a core, a winding and a condenser suitably carried by said core, and a segmental contact insulatedly supported on said coil and connected to said winding, all of said foregoing parts comprising a unitary structure adapted to be secured to the pole pieces of said dynamo, substantially as described.

8. In a dynamo, a generating coil, heads therefor, an insulating block mounted between said heads, a contact member on said block, a terminal on one of said heads, and a condenser carried by said heads and coil and electrically connected to the windings therefor, substantially as described.

9. In a dynamo, a unit coil structure comprising a core, primary and secondary windings carried thereon one end of said primary and secondary windings being connected to said core, a terminal for the remaining end of said primary winding, a head for the coil supporting said terminal, an insulating block adjacent the side of said windings, a terminal carried by said block, a connection between said last mentioned terminal and the free end of said secondary winding, and a condenser carried wholly by said unit coil structure and electrically connected to said primary terminal and said core substantially as described.

In testimony whereof I hereunto affix my signature.

CHARLES THOMAS MASON.
